CLAIM

The ornamental design for a battery charging device, as shown and described.

DESCRIPTION

FIG. 1 is a perspective view of battery charging device taken from the top, right, and front;

FIG. 2 is another perspective view of the battery charging device taken from the bottom, right, and back;

FIG. 3 is another perspective view of the battery charging device taken from the top, right, and front, and showing the battery charging device as it appears with the electrical contact prongs of the battery charging device folded into the body of the device;

FIG. 4 is another perspective view of the battery charging device taken from the bottom, right, and back, and showing the battery charging device as it appears with the electrical contact prongs of the battery charging device folded into the body of the device;

FIG. 5 is a front elevation view of the battery charging device of FIG. 1;

FIG. 6 is a back elevation view of the battery charging device of FIG. 1;

FIG. 7 is a right side elevation view of the battery charging device of FIG. 1;

FIG. 8 is a left side elevation view of the battery charging device of FIG. 1;

FIG. 9 is a top plan view of the battery charging device of FIG. 1; and,

FIG. 10 is a bottom plan view of the battery charging device of FIG. 1.

The broken lines shown in the drawings illustrate portions of the battery charging device that form no part of the claimed design.
